CLAIM

The ornamental design for a dish for microwave baking, as shown and described.

DESCRIPTION

FIG. 1 is a top plan view of a dish for microwave baking, showing my new design;

FIG. 2 is a bottom plan view;

FIG. 3 is a side elevational view, the opposite side being a mirror image thereof; and,

FIG. 4 is a sectional view taken on the line 4—4 of FIG. 1 and illustrating the removable bottom with a circular projecting bead engageable with a registering recess in the annular support flange.
